J. E. McBRIDE

CONVEYER

Filed July 14, 1919

UNITED STATES PATENT OFFICE.

JESSE E. McBRIDE, OF DETROIT, MICHIGAN, ASSIGNOR TO PALMER-BEE COMPANY, OF DETROIT, MICHIGAN, A CORPORATION OF MICHIGAN.

CONVEYER.

Application filed July 14, 1919. Serial No. 310,833.

To all whom it may concern:

Be it known that I, JESSE E. McBRIDE, a citizen of the United States of America, residing at Detroit, in the county of Wayne 5 and State of Michigan, have invented certain new and useful Improvements in Conveyers, of which the following is a specification, reference being had therein to the accompanying drawings.

10 The invention relates to conveyers of that type in which the load is carried by a trolley traveling upon a track which is bent or curved in transverse planes. It is the object of the invention to permit freedom of 15 movement in conformity to the contour of the track and at the same time to support the load without lateral stress upon the conveyer chain. It is a further object to permit of supporting the load at points intermediate the trolleys without lateral stress 20 upon the chain. With these objects in view the invention consists in various features of constructions as hereinafter set forth.

In the drawings:

25 Figure 1 is a side elevation;
Figure 2 is a cross-section;

Figure 3 is a plan view.

A is a track which, as specifically shown, comprises a pair of spaced parallel rails. 30 B are trolley wheels for traveling on the rails A being provided with the flanges C for preventing lateral displacement and being mounted upon a non-revolvable axle D. E is a hanger clamped upon the central portion of the axle D and depending therefrom between the rails of the track A. The hangers E are connected to each other through a series of links F, which are pivotally connected at G to swing in a plane transverse 35 to the plane of rotation of the wheels. There is also provided a pivotal connection H between the links and one of said hangers, permitting a swinging movement in the plane of rotation of the wheels. Thus, in 40 the specific construction shown, the hanger E has projecting laterally therefrom the lug I with which one of the links F is connected by a pin G. While upon the opposite side of the hanger, the link F is connected with another of the links F through 45 the medium of a link J and the transversely-extending pin H. Below the lug I is a bifurcated extension K on the hanger for supporting a hook L to which the load is 50 attached. 55

For certain uses, it is desirable to provide suspension means for the load intermediate the trolleys. If such suspension devices were attached directly to the chain, it would throw an objectionable lateral stress thereon and upon the connecting pivots G. I have, therefore, provided intermediate the hangers rigid longitudinally-extending bearings M which are connected to the depending portion of the hangers E through the 60 medium of links N and O. Along the bars M are arranged a series of hooks P similar to the hooks L and so spaced as to provide for engagement with the load wherever desired. These hooks are preferably connected by providing a pair of bars M between which the eyes of the hooks are arranged to engage cross beams Q.

In use, when the track A is bent in a vertical plane, the pivot pins H will permit 75 an angular movement of the chain sections intermediate the hangers E; on the other hand, where the track is bent or curved in a horizontal plane, the pivots G connecting adjacent links will permit of the corresponding bending of the chain. Where the load is supported by the hooks L, the weight 80 will be carried by the trolleys B through the medium of the hanger E, but if the load is suspended from any one of the intermediate hooks P, the stress will be transmitted through the links M and O to the adjacent hangers E without any lateral stress upon the intermediate portion of the chain. It will also be understood that when 85 the chain is bent or curved in horizontal plane, the rigid bars M will extend as a cord to the curve and the links N and O would compensate for any contraction in length of the chain due to the curvature. 90

What I claim as my invention is:

1. In a conveyer, the combination with a series of trolley wheels mounted thereon, of axles and hangers depending from said axles and directly connected thereto, said hangers being provided with means for attachment of a load, and a link chain connecting said hangers pivoted to swing in transverse planes. 100

2. In a conveyer, the combination with a series of trolley wheels, of hangers depending from said trolley wheels provided with means for attachment of a load thereto, and a link chain connecting said hangers, the portion thereof intermediate said hangers 105

being pivotally connected at one end to swing in one plane and pivotally connected at the opposite end to swing in a transverse plane.

5. 3. In a conveyer, the combination with a series of trolley wheels, of hangers depending from said wheels and provided with means for attachment of a load thereto, a link chain connecting said hangers comprising a series of links intermediate adjacent hangers pivotally connected to each other to swing in a path transverse to the plane of rotation of said trolley wheels and being pivotally connected to one of said hangers to swing in a path parallel to the plane of rotation.

4. In a conveyer, the combination with a track bent or curved in transverse planes, of a series of trolley wheels for traveling on said track, hangers depending from said trolley wheels and provided with means for attachment of a load thereto, and a link chain connecting said hangers, the portions intermediate adjacent hangers comprising a plurality of links pivotally connected to one of the hangers in a plane transverse to the plane of rotation of the trolley wheels and pivotally connected to the opposite hanger in a plane parallel to the plane of rotation of said wheels, a rigid load-carrying member extending between adjacent hangers and supported thereby, and means of attachment between said rigid load-supporting member and hangers permitting limited relative movement of the hangers.

5. In a conveyer, the combination with a track bent or curved in transverse planes, of a series of trolley wheels traveling upon said track, hangers depending from said trolley wheels, a link chain connecting said hangers, the portion thereof intermediate adjacent hangers comprising a plurality of links pivotally connected to each other, and one of the hangers in a plane transverse to the plane of rotation of said wheels and pivotally connected to the opposite hanger in a plane parallel to the plane of rotation of said wheels, a load-carrying bar extending between hangers and supported therefrom, and links forming the supporting connection for said bar from said hanger permitting limited relative adjustment of the latter.

6. In a conveyer, the combination with a trolley wheel, of a hanger depending therefrom and provided at its lower end with means for attachment of a load thereto, a link chain connecting said hanger with similar hangers, the portion of said chain on one side of said hanger being pivotally attached thereto to swing in the plane of rotation of said trolley wheel, and the portion on the opposite side of said hanger being

pivotally connected thereto to swing in a plane transverse to the plane of rotation of said wheel.

7. In a conveyer, the combination with a trolley wheel, of a hanger depending therefrom having a hook at its lower end for attachment of a load and a laterally extending portion intermediate its ends, a link chain connected to said hanger with a portion on one side thereof attached to said laterally extending portion and pivoted to swing in a plane transverse to the plane of rotation of said trolley wheel and the portion upon the opposite side of said hanger being pivoted thereto to swing in a plane parallel to the plane of rotation of said wheel.

8. In a conveyer, the combination with a track, curved or bent in transverse planes and a series of trolley wheels for traveling over said track, hangers depending from said trolley wheels, a link chain for connecting said hangers, the portions thereof intermediate hangers comprising a plurality of links pivotally connected to swing in a plane transverse to the plane of rotation of said wheels, and pivotally connected to one of said hangers to swing in a plane parallel to the plane of rotation of said wheels, a rigid bar extending intermediate hangers, a series of closely spaced load-carrying hooks attached to said rigid bar and to said hangers, and inclined links for attaching the ends of said bar to said hangers permitting of limited relative movement of the latter.

9. In a conveyer, the combination with a series of axles and trolley wheels mounted thereon, of hangers depending from said axles and directly connected thereto, said hangers being provided with means for attachment of a load, and a flexible draft connection between said hangers.

10. In a conveyer, the combination with a series of trolley wheels, of hangers depending from said trolley wheels in substantially the vertical plane thereof and provided with means for attachment of a load, and a flexible draft connection between said hangers.

11. In a conveyer, the combination with a track, of a series of trolley wheels for traveling on said track, hangers depending from said trolley wheels, a link chain connecting said hangers, a rigid load supporting member extending between adjacent hangers and supported thereby, and means of attachment between said load supporting member and hangers permitting limited relative movement of said hangers.

In testimony whereof I affix my signature.

JESSE E. McBRIDE.
